AIRSHIP MOORING

Harold W. Crum and Donald W. Brown, Akron,
Ohio, assignors to Wingfoot Corporation, Wil-
mington, Del., a corporation of Delaware

Application September 22, 1936, Serial No. 101,986

14 Claims. (Cl. 244—115)

This invention relates to lighter-than-air craft and, more particularly, to improvements in mooring devices for such craft. It is especially adapted for non-rigid airships although it may be used for rigid ships as well.

It is frequently desirable to moor an airship outside a hangar or closed building. In many cases the airship is operating in territory where there is no hangar available. In other cases the weather may be such that it is impossible to bring the airship into the hangar without injuring or destroying the airship. In such cases of stormy weather or of excessively windy weather one procedure has been for the airship to ride out the storm in the air. Another has been to moor it to a mast. This is also done in good weather where no hangar is available.

Where a non-rigid airship is moored outside, the only fairly efficient method heretofore has been to attach it to a mast at an under-nose or "belly" position. This has not been satisfactory in all respects, however. For instance, when vertical down gusts of wind occur, an airship moored to an under-nose mast is forced down, causing the top of the mast to protrude into the envelope and thereby forcing open the pressure relief valves. This results in a loss of pressure when the gusts decline. With continued down gusts an airship so moored on an under-nose mast will lose pressure faster than it can be replaced and it is sometimes necessary to pull the rip cord and entirely deflate the ship to prevent the winds from whipping the airship around and actually destroying it.

Several methods of mooring airships at the nose have been known heretofore, too, but none has been satisfactory so far as is known. Some do not work and in others the mooring means are so cumbersome and so inefficient that they are not practical.

It is, accordingly, an object of this invention to provide improved means for mooring airships. Another object is to provide an improved nose mooring device which is simple in form, easily put into operation, and much more safe than devices heretofore used. More specific objects are to provide improvements in attaching a mooring cone to an airship nose, improvements in mooring masts, and improvements in attaching a mooring cone to a mast. Other objects and advantages will become apparent as the description of the invention proceeds.

For a better understanding of the invention reference may be had to the accompanying drawings wherein:

Fig. 1 is a view in side elevation showing an airship moored to a mast in accordance with the invention;

Fig. 2 is a view of a batten with a cable lashed thereto;

Fig. 3 is a view in cross-section of the batten and cable taken along the line 3—3 of Fig. 2;

Fig. 4 is a transverse sectional view through the nose cone which fits over the nose of the airship envelope;

Fig. 5 is a view in cross-section through one of the reinforcing channels of the nose cone which reinforce the nose cone against compression loads taken along the line 5—5 of Fig. 4;

Fig. 6 is a front elevation of the nose cone of Fig. 4;

Fig. 7 is a side elevation showing a cut-off section of the airship, the nose cone assembly, mooring mast and cup, with the mooring cone just ready for engagement in the mooring cup;

Fig. 8 is a cross-sectional view of a portion of the mooring cup with mooring cone in engagement therewith, showing one of the locking means for detachably holding the cone in the cup;

Fig. 9 is a front elevation of the spider-like fitting resiliently associated with the nose cone;

Fig. 10 is a vertical sectional view through the spider-like fitting of Fig. 9;

Fig. 11 is a view of the mast head and mooring cup looking toward the open end of the cup;

Fig. 12 is another view of the mast head and mooring cup showing parts in elevation and parts in cross-section;

Fig. 13 is a cross-section of a fragment of the mooring cup showing one of the latching devices;

Fig. 14 is a fragmentary view of the locking pin which prevents rotation of the mooring cone in the mooring cup.

The principles of the present invention are applicable particularly for nose mooring of non-rigid airships. One of the principal features of the invention is the resilient association of a spider-like fitting with a nose cone, one of which is carried by the airship and the other by a mooring mast. Another feature is found in the system of articulation permitting substantially universal pivoting of the airship with respect to the mast, whereby to provide maximum relief from excessive strains on the ship. Another feature is in the construction details and association of the mooring cup and mast head. Still another feature is in the construction of the mast itself to provide ruggedness and strength with light weight facility in erection.

Referring more particularly to the drawings, an airship 10 having an envelope 12 is shown with its nose moored to the novel mast 11. A plurality of battens 14 strengthen the nose section of the airship envelope 12 and aid in holding a nose cone 16 securely attached thereto. This nose cone 16 may be of the conventional design used on practically all non-rigid airships with the exceptions that its apex is cut off and a flat steel plate 18 welded, riveted, or otherwise united with the remainder of the cone, forming a frustoconical shaped structure, and that a plurality of reinforcing channels 20 for resisting compression loads have been riveted to the inner side of the cone, it having been found advantageous to stiffen the conventional nose cone somewhat because of the forces in compression which are frequently occasioned during the mooring of the ship on the mast. The ends of the battens 14 are held in brackets or sockets 22 of the nose cone, the battens themselves being attached to the airship envelope 12 by conventional means such as cord lacing.

In the drawings twenty-four battens have been shown. This number has been found satisfactory for airships of from 100,000 to 200,000 cubic feet capacity, but it will be understood, of course, that a greater or lesser number may be employed.

A spider-like fitting 24 is resiliently associated with the nose cone 16; said fitting, like the nose cone and the other parts of the mooring device, may be made of steel, duralumin or other suitable material. The fitting 24 is attached to the airship envelope 12 by a plurality of cables 26 which are lashed to the battens 14, the cables terminating in finger patches 28 secured on envelope 12 in conventional manner. In the embodiment of the invention illustrated in the drawings twelve cables are employed, but this number may be varied to requirements of design. The lashing of these cables to the battens is facilitated by thin strips 30 of wood or other material nailed or otherwise secured to the outer edges of each batten to which a cable is to be lashed, thereby providing grooves in which the cables are located. As is shown in Figures 2 and 3, the cables 26 are so maintained in these grooves that they are free to move longitudinally therein, stresses in tension on the cables thus being imparted to the envelope 12 at the finger patches 28. Between the inner surface of the fitting 24 and the flat outer surface 18 of the nose cone 16 and preferably attached to the fitting 24 are a plurality of compression coil springs 32, twelve being employed in the embodiment described. It will thus be seen that the fitting 24 is in resilient association and in floating engagement with the nose cone 16.

Attached to the fitting 24 is a mooring cone 34 by means of a journaled bearing 36 located in the center of the fitting 24 permitting angular rotation about an axis substantially coincident with the longitudinal axis of the airship, and by means of arms 38 and 40 pivoted at bolt 42 permitting movement at right angles to the axis of bearing 36. The mooring cone 34 contains a grooved recess 44 extending circumferentially about the cone. In the recess 44 is located a rectangular slot 45. Attached to the end of mooring cone 34 is a mooring cable 46 which is sufficiently long to reach to the cabin of the airship and also to the ground as the airship is "walked" to the mast.

The mast comprises a trussed tube 49 of appropriate height and a base plate 50 with a stake 52 for anchorage in the ground. The tube 49 and

plate 50 are connected by means of pivot bolts 53 and 54 which permit swinging movement of the tube in two vertical planes at right angles to each other to facilitate erection. They also permit the tube 49 to rest on the ground while the base plate 50 and pin 52 are being anchored in the ground. A plurality of guy wires 56 are attached near the top of the tube 49 and on their other ends contain anchoring stakes 58. Reinforcing truss wires 60 are also spaced about the tube 49 and joined thereto at its bottom end and near its upper end. The tube 49 also is fitted with a number of step brackets 62 for facilitating the climbing of the mast.

Journaled in the upper end of the tube 49 and freely rotatable about the axis thereof is a mast-head 64. To this masthead 64 is bolted a right angle flange 66 containing a pulley 68 over which the mooring cable 46 may be drawn when pulling the ship up to the mast. Bolted or otherwise secured to the flange 66 is a mooring cup 70 which is characterized by a flaring mouth for receiving the mooring cone 34, and three compression spring latches 72 are equally spaced about the cup. These latches 72 extend radially and, when in engaging position, fit into the grooved recess 44 of mooring cone 34 and detachably retain it in mooring cup 70. One of the latches 72, preferably the lowermost one, is provided with a conventional bayonet joint including an offset slot 75 (see Figure 14) which permits deeper engagement of the latch 72 and thus fits in the slot 45 in groove 44. This prevents rotation of the mooring cone 34 in the cup 70. The latches 72 are of conventional design and comprise beveled recess-engaging means 74, compression springs 76, retaining pins 78, and handles 80.

In the operation of the invention, the nose cone 16, spider-like fitting 24, mooring cone 34 and cable 46 are permanently applied to the airship. During flight, the end of the cable 46 is held in the cabin of the airship. When it is desired to moor the airship, the cable 46 is released whereupon it is taken by a ground-crew man and its end led through the mooring cup 70 and over the pulley 68. By means of this cable the airship is pulled into position for mooring and the mooring cone 34 is entered in the cup 70, this being easily accomplished by reason of the fact that the cup 70 is in a horizontal position. When the cone 34 is thus in the cup 70, the latches 72 are released so that their ends 74 fit in the grooved recess 44 and thus retain the airship in moored position.

The cone 34 is rotated by hand until its slot 45 comes into registration with that latch 72 having the bayonet slot 75. The corresponding latch handle 80 is then turned so that the latch end 74 engages in the slot 45 and thus prevents rotation of the cone 34 in the cup 70, and assures the maintenance of bolt 42 in a substantially horizontal position. Also, when it is desired to release the ship from the mast, it is helpful first to disengage the two uppermost latches 72 (those without bayonet slots) from the grooved recess 44 of the cone 34, and then, when the final command is given to release the ship, the man on the mast merely pulls out the third latch 72.

By reason of the bearing 36 in the fitting 24, the pivot 42 and the rotatable mast head 64, the ship is universally joined to the mast. In other words, limited movement of the ship in any direction is permitted. Also, the initial force of any gust of wind is taken up by the floating association of the spider-like fitting 24 with the nose cone 16 wherein the resilient springs 32 and the

cables 26 act as a shock absorber and diminish the danger by distributing the wind forces about the airship.

It will be understood that while the springs 32 are preferably helical coils, cylindrical coil springs may be used. Also, they may be attached to the nose cone 16 instead of to the fitting 24, but the latter is preferable. Their size and strength may be varied, too, according to the size of the airship.

10 Also, resilient means other than spring may be employed, for example, rubber cushions.

By the improved mooring device of this invention an airship may be moored successfully at its nose. Furthermore, when so moored, it will 15 withstand much greater wind velocities without danger than has been possible heretofore. In fact, an airship is usually safer in a storm when moored according to this invention than when riding-out the storm in the air. Thus, an airship 20 moored by this invention has safely withstood wind velocities of seventy miles per hour. Transverse roll even in winds of a 70 mile per hour velocity is not over 10°. Axial torsion is not excessive and the wheel of the airship located under 25 the cabin does not grind into the ground. Furthermore, there is no substantial loss of pressure. That the invention is of great merit is apparent.

Although only one form which the invention 30 may assume has been illustrated and described in detail, it will be apparent to those skilled in the art that the invention is not so limited, but that various modifications may be made therein without departing from the spirit of the invention or from the scope of the appended claims, 35 wherein it is intended to cover all features of patentable novelty residing in the invention.

What we claim is:

1. A moored airship comprising in combination with the airship, a nose cone comprising a frusto-conical shaped structure fitted over the nose end of the envelope of said airship and securely attached thereto by means including a plurality of battens terminating in said nose cone and extending radially at spaced intervals about the 45 circumference of the airship, a spider-like fitting located over the outer end of said nose cone and including resilient springs for association with the outer end of said nose cone, said fitting being attached to the airship by means of a plurality of 50 cables slidably lashed in said battens and terminating in finger patches attached to the envelope, a mooring cone adjustably connected with said spider-like fitting by means which permit tilting of the airship in different planes, a mooring 55 cable extending from said mooring cone; a mooring mast extending vertically from the ground and attached to the ground by means of a base including a pointed stake or pin anchored in the ground, pivoting means connecting said 60 base and said mast and permitting said mast to be laid on the ground while operatively engaging the base with the ground, a plurality of cables attached to the upper part of the mast and to the ground at spaced intervals about the base, 65 a plurality of steps attached to the mast; a mast head comprising a journaled bearing fitted in the upper end of said mast and freely rotatable in a plane at right angles to the axis of said mast, a mooring cup attached to said bearing, said cup 70 comprising a receptacle receiving said mooring cone in a horizontal plane, and locking means for detachably holding said cone in said receiving receptacle, said locking means including means preventing the rotation of said mooring cone in 75 said receiving receptacle.

2. A moored airship comprising in combination with the airship, a nose cone comprising a frusto-conical shaped structure fitted over the nose end of the envelope of said airship and securely attached thereto by means including a plurality of 5 battens terminating in said nose cone and extending radially at spaced intervals about the circumference of the airship, a spider-like fitting located over the outer end of said nose cone and including resilient springs for association with the 10 outer end of said nose cone, said fitting being attached to the airship by means of a plurality of cables slidably lashed in said battens and terminating in finger patches attached to the envelope, a mooring cone adjustably connected with 15 said spider-like fitting by means which permit tilting of the airship in different planes, a mooring cable extending from said mooring cone, a mooring mast, a mast head comprising a journaled bearing fitted in the upper end of said mast and rotatable in a plane at right angles to the axis of said mast, a mooring cup attached to said bearing, said cup comprising a receptacle receiving said mooring cone in a horizontal plane, and locking means for detachably holding said cone 20 in said receiving receptacle, said locking means including means preventing the rotation of said mooring cone in said receiving receptacle.

3. A moored airship comprising in combination with the airship, a nose cone comprising a 30 frusto-conical shaped structure fitted over the nose end of the envelope of said airship and securely attached thereto by means including a plurality of battens terminating in said nose cone and extending radially at spaced intervals 35 about the circumference of the airship, a spider-like fitting located over the outer end of said nose cone and resiliently associated with the outer end of said nose cone, said fitting being attached to the airship by means of a plurality of 40 cables slidably lashed in said battens and terminating in finger patches attached to the envelope, a mooring cone adjustably connected with spider-like fitting by means which permit tilting of the airship in different planes, a mooring cable 45 extending from said mooring cone, a mooring mast, a mast head comprising a journaled bearing fitted in the upper end of said mast and freely rotatable in a plane at right angles to the axis of said mast, a mooring cup attached to said 50 bearing, said cup comprising a receptacle receiving said mooring cone in a horizontal plane, and locking means for detachably holding said cone in said receiving receptacle, said locking means including means preventing the rotation of said mooring cone in 55 said receiving receptacle.

4. A moored air ship comprising in combination, a nose cone seated on the nose of the airship, a spider-like fitting attached to the airship and located over the outer end of said nose cone 60 but spaced therefrom, resilient cushioning means between the nose cone and said spider-like fitting, a mooring cone hingedly connected with said spider-like fitting by means which permit tilting of the airship in different planes, a mooring cable extending from said mooring cone, a mooring mast, a rotatable journaled bearing fitted in the upper end of said mast, a mooring cup attached to said bearing, said cup comprising a receptacle receiving said mooring cone in 70 a horizontal plane, and locking means for detachably holding said cone in said receiving receptacle.

5. In an airship mooring device, a body member adapted for attachment to the nose of an 75

- 5 airship and to be carried thereby, resilient compression members also carried by the airship and serving as cushioning means between said body member and the nose of the airship, and a cable fitting associated with the outer side of said body member.
- 10 6. An airship mooring device comprising a spider-like body member, means including a plurality of cables for floatably attaching said member to the airship, said cables being secured to the airship at spaced intervals about its circumference, a plurality of resilient compression springs attached to the inner side of said body member, and a cable fitting associated with the outer side of said body member.
- 15 7. An airship mooring device comprising a body member floatably attached to the nose of an airship, a plurality of cables effecting such attachment, resilient cushioning means acting between the inner side of said body member and the nose of the airship, a mooring cone pivotally connected to said body member, and a cable associated with said mooring cone.
- 20 8. An airship mooring device comprising a spider-like body member, means including a plurality of cables for floatably attaching said member to the airship, said cables being secured to the airship, resilient cushioning means attached at the inner side of said body member, and a mooring cone adjustably connected to the outer side of said body member by means which permit tilting of the airship in different planes.
- 25 9. In mooring apparatus for airships a nose cone assembly comprising a frusto-conical shaped cap, means for attaching said cap over the nose end of an airship, said means comprising a plurality of battens secured to the airship envelope at substantially uniformly spaced intervals about its circumference, a spider-like fitting for said cap, means for securing said fitting in floating engagement with the outer surface of said cap such means including a plurality of compression springs, means for attaching said fitting to the airship, said means comprising cables laced over said battens and terminating in finger patches applied to the envelope, and a mooring cone adjustably connected with said spider-like fitting by means which permit tilting of the airship in different planes.
- 30 10. In combination with an airship, a resiliently cushioned fitting mounted on and spaced from the nose of said airship, a mooring mast, and cooperating means for detachably connecting said fitting to said mast, said cooperating means comprising a mooring cone and a mooring cup. 5
- 15 11. In combination with an airship, a resiliently cushioned fitting mounted on and spaced from the nose of said airship, a mooring mast, and cooperating means for detachably connecting said fitting to said mast, said cooperating means comprising a mooring cone and a mooring cup, said mooring cone being attached to said resiliently yieldable fitting and said mooring cup being attached to said mast. 15
- 20 12. In combination with an airship, a resiliently cushioned fitting mounted on and spaced from the nose of said airship, a mooring mast, and cooperating means for detachably connecting said fitting to said mast, said cooperating means comprising a mooring cone and a mooring cup, said mooring cone pivotally attached to said resiliently yieldable fitting by means which permit tilting of the airship in different planes. 20
- 25 13. In combination with an airship, a resiliently cushioned fitting mounted on and spaced from the nose of said airship, a mooring mast, and cooperating means for detachably connecting said fitting to said mast, said cooperating means comprising a mooring cone and a mooring cup, said mooring cone being attached to said resiliently yieldable fitting by two pivots located in a substantially horizontal plane but at right angles to each other. 30
- 30 14. In nose-mooring apparatus for airships, a nose cone assembly comprising a frusto-conical-shaped structure fitted over the nose end of the envelope of the airship and securely attached thereto, a spider-like fitting placed over the outer end of said structure and in resilient association therewith, said fitting being attached to the envelope at spaced intervals about the circumference of the envelope, and a mooring cone attached to said fitting. 40
